UNITED STATES PATENT OFFICE.

GEORGE F. SEARS, JEHN H. PROSE, AND ROSEMOND T. ANDERSON, OF HUNTINGTON,
WEST VIRGINIA.

AUTOMOBILE-CURTAIN AND MOUNTING.

1,134,641.

Specification of Letters Patent.

Patented Apr. 6, 1915.

Application filed January 9, 1914. Serial No. 811,225.

To all whom it may concern:

Be it known that we, GEORGE F. SEARS, JEHN H. PROSE, and ROSEMOND T. ANDERSON, citizens of the United States, residing at Huntington, in the county of Cabell, State of West Virginia, have invented certain new and useful Improvements in Automobile-Curtains and Mountings; and we do hereby declare the following to be a full, clear, and exact description of the invention, such as will enable others skilled in the art to which it appertains to make and use the same.

This invention relates to automobile tops, and more particularly to the side curtains thereof, and has for its object to provide a curtain of this kind which may be quickly and easily brought into and out of operative position.

Another object is to provide such a curtain which will have a maximum transparent area, and which will be so arranged that it may be brought into inoperative position without damage to the transparent portions.

Another object is to provide such a curtain which will be so mounted as to present no interference with the raising or lowering of the top.

In the drawings: Figure 1 is a side elevation of an automobile top provided with the present curtain, a portion of the top being cut away to illustrate parts of the structure. Fig. 2 is a horizontal section on the line 2—2 of Fig. 1 showing one side of the top and the mounting of the curtain. Fig. 3 is a view showing the roller shifted to lie against the rear top bow to permit folding of the top. Fig. 4 is a detail view showing the top mounting of the roller with the roller in vertical position. Fig. 5 is a detail view of the bow rest iron and the roller mounting carried thereby. Fig. 6 is a longitudinal section through portions of the roller. Fig. 7 is a detail perspective view showing a portion of the track wire and the connection of the curtain thereto. Fig. 8 is an enlarged perspective view showing the curtain provided with a foldable forward extension. Fig. 9 is a section on line 9—9 of Fig. 1.

Referring now to the drawings, there is shown a portion of an automobile body 10 provided with a top of the usual type including an upright bow 11, a diagonal rearward bow 12 pivoted to the bow 11, and in-

cluding also a forward upright bow 13 and a front stretching bow 14. These parts are such as are found in the usual automobile top, and have mounted thereon the usual top fabric 15.

Secured to the rearward bow 12 and over the top fabric 15 there is a curved plate 16 carrying a pair of rearwardly extending apertured ears 17 and 18, between which there is mounted for pivotal movement an ear 19 carried by an extensible member 20 consisting of a section 21 which carries the ear 19 and a second section 22 which is connected with the section 21 by means of a threaded bar 23 engaged in threaded openings 21^a and 22^a formed in the mutually adjacent faces of the two sections. The section 22 carries an ear 24 at its outer end, and there is thus provided the complete extensible member 20, its extension being effected by turning the two parts with respect to each other to separate them on the threads of the bar 23.

The ear 24 has an eye 25 which receives the upper end of a shaft 26 upon which there is revolvably mounted on ball bearings, a curtain roller 27. This roller has secured concentrically therewith at its upper end a winding drum 28 having a channel 29 in its periphery, to receive a cord 30 to be later described.

The under surface of the drum 28, projecting toward the roller, is beveled at its edges as shown at 31 to facilitate the winding of the curtain 32 which is secured to the roller, upon the latter, thus preventing any interference with such winding through engagement of the edge of the curtain with the edge of the drum. The lower end of the shaft 26 is removably engaged in a mounting carried by the bow rest iron 32'. This iron is of peculiar shape, and is designed to accommodate the curtain in the present invention. As illustrated especially in Fig. 5, this bow rest iron consists of a vertical portion 33 which is engaged in the bow rest eye 34 carried by the car. The lower part of the portion 33 is bent outwardly and laterally as shown at 35 and is then bent upwardly parallel to the portion 33 as shown at 36, beyond which its extremity 105 is turned out at right angles as shown at 37 to receive the bow rest 38. There is thus formed a space 39 between the two portions

33 and 36 for a purpose to be presently described.

Formed on the portion 33 there are a pair of upper and lower spaced resilient ears 40 and 41 between which there is pivoted a horizontal plate 42, the pivotal mounting of which is accomplished by a bolt 43 passed through the eyes 40 and 41 and through an ear 44 carried by the plate 42, it being understood that this bolt may be tightened to hold the plate 42 against pivotal movement. The plate 42 has a plurality of peripheral notches 45, any one of which may receive the lower end of the shaft 26 of the roller 27, and it will be seen that when the shaft is so engaged the roller will be held vertically at the back of the top.

The curtain 32 is rolled upon the roller 27 so as to pass from the roller at the outer side thereof and the space 39 above referred to is provided for the passage of the curtain therethrough when it is drawn into operative position along the side of the car. To support the upper edge of the curtain 32 a track wire 46 is secured at its ends to the foremost and rearmost bows of the top and is suitably mounted on brackets secured to the other bows, as indicated at 47, and the upper edge of the curtain is provided with a hook 48 which engages over and run upon the wire.

To effect the rolling of the curtain upon the roller 27 and its unrolling therefrom, the cord 30 is secured to the winding surface 35 of the drum 28, from which it is carried forwardly to and around a pulley 50 carried by the stretching bow 14 from which it is carried rearwardly and is secured to the upper forward corner of the curtain. It will thus be seen that when the inner length 40 of the cord 49 is moved rearwardly, the curtain will be pulled forwardly and will be unwound from the roller, and since the cord is engaged with the drum, it will be wound thereupon at its rearward end. Reverse movement of the cord results in its unwinding from the drum, the latter being thus rotated to wind the curtain thereupon. In this way the curtain may be 45 moved into and out of operative position.

Now it will be readily seen that since the curtain winds in a scroll over the roller while the cord unwinds from the drum the resultant increase in the size of the roll of the curtain would result in a slackening of the cord 30, which not compensated for would cause the curtain to sag. To prevent this sagging of the curtain and keep the cord at all times taut, the cord is provided with 55 an extensible elastic section 51 which is illustrated in the drawings as a helical spring led into the length of the cord. Thus, as the curtain unwinds and the cord receives 60 more tension, this is compensated for by the stretching of the spring, and when the cur-

tain winds up and the cord slackens, the spring takes up the slack.

So much for the mounting and operation of the curtain when the top is raised. When it is desired to lower the top, it is obvious 70 that a provision must be made for the disposition of the roller 27, and the curtain which has been wound thereon. It will be remembered that the lower end of the shaft 26 of the roller 27 has been described as being removably engaged in one of the notches 45 of the plate 42. It will also be remembered that the member 20 consists of two sections which are movable pivotally with respect to each other and that this member 80 is pivoted by means of its ear 19 to the plate 16 which is carried by the top of the automobile. This arrangement permits of universal movement of the upper end of the roll when the lower end of the shaft is disengaged from the plate 42 and by reason of this structure the lower end of the roller may be swung out from the car, around the bow rest iron 32 and may then be brought against the rearmost top bow 12 to which it 90 may be secured by a strap 52 or any other suitable fastener. When thus disposed the roller interferes in no way with the lowering of the top. The extensible function of the member 20 makes it possible to vary the 95 distance between the upper end of the roller and the bow 12 so as to accommodate the device to cars of different specific dimensions and so as to also accommodate between the roller and the bow, any metal bow clamp 100 such as is used in some instances for fastening the bows in folded position. The pivotal mounting of the plate 42 which receives the lower end of the roller also permits of 105 adjustments to suit different tops and a further adjustment is provided for by the inclusion of the plurality of notches 45 any one of which is adapted to receive the lower end of the shaft 26.

In some makes of automobiles it may be 110 inconvenient or impossible to mount the roller 50 at the foremost point to which it is desired to bring the curtain, and there is a provision for such contingencies illustrated in Fig. 8 of the drawings in which the curtain is provided with an extended portion 115 at its forward edge, detached from the cord 49 except for its connection with the main portion of the curtain, and which is adapted to be folded against the inner surface of the curtain, where it is held by suitable snap fasteners. This extension is indicated at 52' and when the curtain has been drawn out full length this extension may be unsnapped and carried forward to the desired point. 120 One or more buttons or other fasteners may be provided for the lower edge of the curtain as indicated at 54.

The ends of the shaft 26 are threaded and are provided with wing nuts 55 and 56 which 130

may be operated to hold the shaft immovable in its top and bottom mountings, and the lower end of the roller 27 is provided with a flange 57 having its edges flared away from the roller to facilitate the winding of the curtain on the latter.

As illustrated in the drawings, the mounting of the hook 48 upon the curtain 32 is accomplished through the medium of a relatively short cord or wire 58, of sufficient flexibility to permit it to wind upon the roller, this wire being secured at its ends to the curtain and extending longitudinally thereof, the wire being passed through an eye 59 formed in the hook so that when the hook has reached the roller 50, the curtain may be still drawn forwardly until the eye of the hook reaches the rearward end of the member 58. The guide wire 46 upon which 20 the hook runs is of course sufficiently flexible to permit folding of the top and is preferably a wire cable.

There is of course an eyelet 60 in the back curtain 61 of the automobile top through 25 which the cord 30 passes to the drum 28.

What is claimed, is:—

1. The combination with a vehicle top of a revolvably mounted roller adjacent to the top, a winding drum carried by the roller, 30 a curtain engaged with the drum and adapted to be wound thereupon or to be extended in operative relation to the top, a flexible member connected with the curtain, a rotatable mounting for the flexible member located at a point spaced from the roller, said flexible member being carried around and beyond the mounting to the roller and engaged therewith to be wound thereupon, a track, slidable connections between the curtain and the track, and an extensibly yieldable section in said flexible member.

2. The combination with a vehicle having a foldable top of a revolvble roller connected at its upper end with the top for universal movement with respect to the top, said connection being adjustable to vary the distance between the roller and the top, a bow rest iron connected with the vehicle and including horizontally spaced portions, a 45 bow rest connected with one of said portions, means for detachably connecting the lower end of the roller with the bow rest iron, a curtain carried by the roller and adapted to be extended therefrom through 50 the space between the portions of the bow rest iron to lie at a side of the top, said 55 roller being adapted for movement upon its universal connection to pass the bow rest

iron and lie against the top when detached at its lower end from the bow rest iron. 60

3. The combination with a vehicle and a top therefor of a curtain roller connected at its upper end with the top for adjustment toward and away from the top, a plate pivotally connected with the vehicle for 65 movement toward and away from the latter, said plate having a plurality of peripheral notches, means for holding the plate at different points of its pivotal movement, means carried by the roller for engagement 70 in the different notches interchangeably and a curtain carried by the roller and adapted to be wound thereupon or extended therefrom.

4. The combination with a vehicle and a 75 foldable top therefor of a curtain roller removably connected at its upper end with the top for adjustment toward and away from the top, a plate pivotally connected with the vehicle for movement toward and away from 80 the latter, said plate having a plurality of peripheral notches, means for holding the plate at different points of its pivotal movement, means carried by the roller for removable engagement in the different notches interchangeably and a curtain carried by the roller for 85 extended therefrom, said roller being movable upon its top connection when disengaged at its bottom to lie against the top to 90 permit folding of the latter.

5. The combination with a vehicle having a foldable top of a revolvble roller connected at its upper end to the top and normally arranged vertically, a vertical drum secured 95 to said roller, a curtain on said drum, a pulley attached to the top of the vehicle in advance of the roller and in spaced relation thereto, a flexible member surrounding and attached to the roller and passing forwardly 100 over the pulley and thence backwardly and attached to the forward edge of the curtain, and a spring interposed in said flexible member to hold the said member taut, whereby the curtain on the drum may be 105 opened any desired distance and maintained in such position.

In testimony whereof, we affix our signatures, in the presence of two witnesses.
